A. J. E. RYLANDER

VESSEL PROPELLING AND CONTROLLING DEVICE

Original Filed May 31, 1922

Inventor
A. J. E. Rylander

UNITED STATES PATENT OFFICE.

ANDERS JOHAN EMIL RYLANDER, OF STOCKHOLM, SWEDEN.

VESSEL PROPELLING AND CONTROLLING DEVICE.

Application filed May 31, 1922, Serial No. 564,905. Renewed August 26, 1924.

To all whom it may concern:

Be it known that I, ANDERS JOHAN EMIL RYLANDER, a subject of the King of Sweden, residing at Katarina Kyrkobacke 2, Stockholm, in the Kingdom of Sweden, have invented certain new and useful Improvements in Vessel Propelling and Controlling Devices, of which the following is a specification.

10 This invention relates to vessel propelling and controlling devices, and is particularly directed to the manner of controlling the speed and direction of a craft, to which an outboard motor is attached, and to the manner of cooling the motor.

In the accompanying drawing which is to be taken as a part of this specification, and in which I have shown a merely preferred form of embodiment of the invention:

20 Figure 1 is a side elevation of an outboard motor constructed in accordance with the provisions of this invention.

Fig. 2 is a plan view of a part of the speed and direction controlling arrangement.

25 Fig. 3 is a vertical section of a part of the device on the line 3—3.

Referring to the drawings, 1 indicates the motor which may be of any suitable or usual construction, and 2 the main standard, 30 through which the driving shaft 3 rotatably extends. The main standard 2 is turnably supported in a bracket clamp (not shown), which is detachably connected to the heck of the craft in any suitable manner. The standard 2 surrounds the upper part of a sleeve or tube 4 that is rigidly secured to the motor 1 and in its turn surrounds the driving shaft 3. The driving shaft is by a bevel gear 5 in the usual manner connected 40 to a hollow propeller shaft 6, to which the propeller 7 is secured. The gear 5 and the front part of the shaft 6 are enclosed in a cap 8.

Rigidly attached to the tube 4 and the cap 45 8 is a substantially U-shaped, vertical frame 9 facing the propeller with its open part. To the vertical rear part of this frame 9 are hinged two plates 10 and 11, and to the top and bottom edges of these plates are 50 hinged other triangular plates 12, which in pair are hinged to each other, as is shown in Figs. 2 and 3, thereby forming a pocket when the plates are expanded, Fig. 2, but flat in engagement with each other when 55 the plates are collapsed, Fig. 3. The plates

12 lie in the collapsed position between the plates 10 and 11.

Links 13 are pivotally connected, as at 15, to horizontal groove shaped parts 14 of the plates 10 and 11 respectively, and are 60 also pivotally connected to a rod 16 that passes through the hollow propeller shaft 6 and on its forward part is formed as a rack 17. The grooves 14 are shown integral with the plates 10 and 11 and formed by a 65 curvature of the plates. The rack gears with a pinion 18 secured on the lower end of a vertical rod or tube 19, to the upper end of which is secured a pinion 20 gearing with a rack 21 on a slide 22, that is slidably mounted in a bracket 23 extending from the main standard 2. Another rack 24 on the slide 22 gears with a toothed segment 25 pivotally supported, as at 26, by consoles 27 on the bracket 23. Rigidly connected to the segment 25 is an arm 28 ending in a handle 29.

The parts 23, 28 and 29 form in conjunction a steering lever or tiller, by which the outboard motor is turned as a whole for steering purpose.

Preferably the vertical tube 19 is connected to the cooling jacket of the motor 1 at its upper end by a tube 30, and at its lower end connected to a water-circulating pump 31 by any suitable channel system 85 in the cap 8.

On lifting or lowering the arm 28, the tube 19 will be rotated and the rod 16 forced to slide in the hollow propeller shaft 6. By means of the links 13 the plates thereby 90 are opened or collapsed. In their opened condition they form a pocket that deflects the water stream coming from the propeller, whereby the craft is reversed. In an intermediate position of the plates, the craft 95 will be stagnant, although the propeller 7 rotates continuously.

As many changes could be made in this construction without departing from the scope of the following claims, it is intended 100 that all matter contained in the above description or shown in the accompanying drawing shall be interpreted as illustrative only and not in a limiting sense.

I am aware that prior to my invention collapsible reversing rudders have been made. I therefore do not claim such rudders broadly; but

I claim:

1. In a collapsible reversing rudder, the 110

- combination with two vertical rudder plates normally flat in engagement with each other and hinged to each other at their rear edges, of upper and lower plates having their edges 5 hinged to each other and to the upper and lower edges of said rudder plates, said upper and lower plates being hingeable inwardly and covered by said rudder plates in their collapsed position.
- 10 2. In a collapsible reversing rudder, in combination, two vertical rudder plates normally flat in engagement with each other and hinged to each other at their rear edges, upper and lower plates having their edges 15 hinged to each other and to the upper and lower edges of said rudder plates, said upper and lower plates being hingeable inwardly and covered by said rudder plates in their collapsed position, and means for opening 20 and closing said rudder.
3. In a collapsible reversing rudder for vessels, in combination, two vertical rudder plates normally flat in engagement with each other and hinged to each other at their rear 25 edges, a frame supporting said rudder plates and turnably carried by the vessel, upper and lower plates having their edges hinged to each other and to the upper and lower edges of said rudder plates, said upper and lower 30 plates being hingeable inwardly and covered by said rudder plates in their collapsed position, and means for opening and closing said rudder.
4. In a vessel propelling and controlling 35 device, the combination of a collapsible reversing rudder, a propeller, a hollow propeller shaft, a slidable rod passing through said hollow propeller shaft and connected to said collapsible rudder, and means for moving 40 said rod fore and aft.
5. In a vessel propelling and controlling device, the combination of a collapsible reversing rudder, a propeller, a hollow propeller shaft, a slidable rod passing through 45 said hollow propeller shaft and connected to said rudder, a rack on said rod, a pinion engaging said rack, a shaft supporting said pinion, and means for rotating said shaft.
6. A vessel propelling and controlling device as set forth in claim 5, and wherein the 50 pinion supporting shaft is tubular.
7. A vessel propelling and controlling device as set forth in claim 6, and wherein the tubular shaft is connected with the motor jacket at its one end and with the water 55 circulating pump at its other end.
8. In a vessel propelling and controlling device, the combination of a collapsible reversing rudder, a rod connected to said rudder, a rack formed on said rod, a pinion engaging said rack, a vertical shaft rigidly supporting said pinion at its lower end, a pinion 60 rigidly connected to the upper end of said vertical shaft, a rack engaging said last mentioned pinion, and means for moving said 65 last mentioned rack fore and aft.
9. A vessel propelling and controlling device as set forth in claim 8, and wherein the vertical shaft is tubular and connected at its upper end to the motor jacket and at its 70 lower end to the water circulating pump.
10. In a collapsible reversing rudder, the combination of two rudder plates normally flat in engagement with each other, grooves arranged in said plates, said grooves forming in section a U-shaped extension of the plates, links engaging said grooves and hinged to said plates, a rod pivotally connected to said links, and means for moving 75 said rod fore and aft for opening and closing said rudder.
11. A collapsible reversing rudder as set forth in claim 10, and wherein the grooves are integral with the plates and formed by a 80 curvature of the plates.
12. In a collapsible reversing rudder as set forth in claim 10, and wherein the plates are vertical, the combination with the plates of upper and lower plates having their edges hinged to each other and to the upper and 85 lower edges of the first mentioned plates, said upper and lower plates being hingeable inwardly and covered by the first mentioned vertical plates in their collapsed position.

ANDERS JOHAN EMIL RYLANDER.
